US00D910576S

(12) **United States Design Patent** (10) **Patent No.:** **US D910,576 S**
(45) **Date of Patent:** **** Feb. 16, 2021**

(54) **ADAPTER**

(71) Applicant: **JUUL Labs, Inc.**, San Francisco, CA (US)

(72) Inventors: **Brandon Cheung**, San Francisco, CA (US); **Kevin Lomeli**, San Francisco, CA (US); **Claire O'Malley**, San Francisco, CA (US)

(73) Assignee: **JUUL Labs, Inc.**, San Francisco, CA (US)

(**) Term: **15 Years**

(21) Appl. No.: **29/660,826**

(22) Filed: **Aug. 22, 2018**

(51) **LOC (13) Cl. 13-03**

(52) **U.S. Cl.**

USPC **D13/147**

(58) **Field of Classification Search**

(57) **CLAIM**

The ornamental design for an adapter, as shown and described.

DESCRIPTION

FIG. 1 is a top, front, and right side perspective view of an adapter, showing our new design;

FIG. 2 is a top, rear, and right side perspective view thereof;

FIG. 3 is a top, rear, and right side perspective view thereof;

FIG. 4 is a bottom, front, and left side perspective view thereof;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a rear view thereof.

The dash-dash broken lines illustrate portions of the adapter that form no part of the claimed design.

1 Claim, 6 Drawing Sheets
